UNITED STATES PATENT OFFICE.

FRANK SCHLICKER, OF WILLOCK, PENNSYLVANIA.

RAIL-FASTENER.

No. 851,442.

Specification of Letters Patent.

Patented April 23, 1907.

Application filed February 18, 1907. Serial No. 358,110.

To all whom it may concern:

Be it known that I, FRANK SCHLICKER, a citizen of the United States of America, residing at Willock, in the county of Allegheny and State of Pennsylvania, have invented certain new and useful Improvements in Rail-Fasteners, of which the following is a specification, reference being had therein to the accompanying drawings.

10 This invention relates to rail fasteners, and the invention has for its object to provide a simple and inexpensive fastener for firmly holding a rail upon a tie and preventing lateral displacement of the same.

15 My improved rail fastener is designed to embrace the base and web portion of a rail, adding rigidity and strength to the rail and preventing the rail from creeping upon the ties.

20 The detail construction of my invention will be presently described and then specifically pointed out in the appended claims, and referring to the drawing forming part of this specification, like numerals of reference 25 designate corresponding parts throughout the several views, in which:—

Figure 1 is a perspective view of the rail fastener, Fig. 2 is an end view of the same, Fig. 3 is a plan of the fastener illustrating 30 one of the pivoted fish bars thereof in an open position, Fig. 4 is a vertical sectional view of the fastener.

To put my invention into practice, I construct my fastener of two end plates 1 having 35 upwardly extending lugs 2. The end plates are connected by straps 3, said straps being provided with spike notches 4.

Pivotaly mounted between the pierced lugs 2 are fish bars or plates 5, said bars or 40 plates being provided with trunnions 6 adapted to engage in said pierced lugs. The fish bars or plates 5 have their outer edges notched, as at 7, whereby when said fish bars or plates are folded inwardly to 45 embrace the base 8 and web portion 9 of a rail 10, said notches 7 will register with the notches 4 of the straps 3.

Spikes 11 are driven through the notches 4 and 7 into the tie 12 supporting the rail 10. The heads of the spikes overlie the fish bars 5 or plates 5 and firmly retain said bars or plates upon the base flanges 8 of the rail 10.

The end plates 1 serve to protect the edges of the tie 12 beneath the rail 10 while the fish bars 5 and the spikes 11 prevent 55 lateral and vertical displacement of said rail.

What I claim and desire to secure by Letters Patent, is:—

1. The combination with a tie and a rail 60 mounted thereon, of end plates having upwardly extending pierced lugs, notched straps connecting said end plates, fish bars or plates trunnioned in said pierced lugs, and adapted to embrace the base flanges and 65 web portion of said rail, said fish bars or plates having notches formed therein adapted to register with the notches of said straps, and spikes extending through said notches into said tie and overlying said fish bars or 70 plates.

2. In a rail fastener, the combination with a tie and a rail mounted thereon, of connected end plates adapted to embrace the sides of said tie, fish bars or plates trunnioned 75 between said end plates and engaging the base flanges and web portion of said rail, and spikes mounted in said tie and engaging said fish bars or plates.

3. In a rail fastener, the combination with 80 a tie and a rail mounted thereon, of connected end plates adapted to embrace the sides of said tie, fish bars or plates trunnioned between said end plates and engaging the base flanges and web portion of said rail, 85 and means carried by said tie for holding said fish bars or plates in engagement with said rail.

In testimony whereof I affix my signature in the presence of two witnesses:

FRANK SCHLICKER.
